CIRCUIT INTERRUPTER

Benjamin P. Baker, Turtle Creek, and Herbert J. Webb, Forest Hills, Pa., assignors to Westinghouse Electric & Manufacturing Company, East Pittsburgh, Pa., a corporation of Pennsylvania

Application April 7, 1942, Serial No. 437,958

11 Claims. (Cl. 200—82).

The invention relates to electric circuit interrupters and, more particularly, to circuit interrupters of the fluid pressure operated type.

An object of the invention is the provision of a circuit interrupter with an improved fluid pressure operating means for controlling the movement of the contact means.

Another object of the invention is the provision of a circuit interrupter with a fluid operating means for effecting high speed operation of the contact means, said operating means embodying an improved fluid shock-absorbing system for smoothly decelerating the moving parts at the end of the stroke.

Another object of the invention is the provision of a circuit interrupter having a compressed gas operating piston for effecting high speed operation of the contact means, and an improved shock-absorbing means comprising an automatic valve which permits free flow of operating compressed gas into the operating cylinder and which normally throttles the reversely flowing exhaust gas a predetermined amount.

Another object of the invention is the provision of a compressed gas-operated circuit interrupter embodying a shock-absorbing system as described in the preceding paragraph, and wherein the throttle valve throttles the reversely flowing exhaust gas a lesser amount whenever a reverse switching operation occurs within a predetermined short time interval after the valve has been opened by forwardly flowing gas into the cylinder.

Another object of the invention is the provision of a compressed air operated circuit interrupter with an improved air shock-absorbing system comprising an automatic throttle valve which is opened by the forward flow of compressed air into the interrupter operating cylinder and closed after a predetermined short time delay following operation of the breaker, said valve in the closed position acting to partially throttle reversely flowing air exhausted from the cylinder.

The novel features that are considered characteristic of the invention are set forth in particular in the appended claims. The invention itself, however, both as to structure and operation, together with additional objects and advantages thereof, will be best understood from the following detailed description of a preferred embodiment when read in conjunction with the accompanying drawings, in which:

Figure 1 is a side elevational view of a circuit interrupter embodying the features of the present invention;

Fig. 2 is a fragmentary sectional view, on an enlarged scale, showing the contact operating means of the circuit interrupter and the shock-absorbing system for the movable disconnect contact member of the interrupter;

Fig. 3 is a detail sectional view on an enlarged scale of one of the automatic throttle valves;

Fig. 4 is a sectional view, on an enlarged scale, of the arcing contact operating means and the dump valves;

Fig. 5 is a fragmentary enlarged view, partly in section, showing the blast valve mechanism; and

Fig. 6 is a fragmentary view, partly in section showing the opening and closing control valves of the interrupter.

The features of the present invention are illustrated as applied to a circuit interrupter of the same general construction as fully disclosed in the copending application of L. R. Ludwig et al., Serial No. 431,394, filed February 18, 1942, and assigned to the assignee of the present application.

Referring to the drawings, the reference numeral 11 indicates a framework which may be formed of structural steel or other suitable material. Rising from the left-hand side of the framework are a plurality of hollow insulators 13, 15 and 17, only the first two of which are shown in Fig. 1, the latter being shown in Fig. 2. Supported upon the upper end of the insulators 13, 15 and 17 is a casing 19 for housing the operating means more clearly shown in Fig. 2. The casing 19 supports a hollow insulator 21 which, in turn, supports a circuit interrupting element 23.

A hollow insulator 25 extends upwardly from the element 23 and has a metallic terminal cap 27 secured on its free end. A stationary contact member 29 extends downwardly from the terminal cap 27 into the circuit interrupting element 23. A movable contact member 31 coacts with the stationary contact member 29 and extends downwardly through the element 23 and through the hollow insulator 21. The lower end of the contact member 31 extends into the casing 19 and is connected to a piston of the operating means as shown in Fig. 2, and which will be more fully described hereinafter.

The contacts 29—31 form arcing contacts of the interrupter and are electrically connected in series with a pair of disconnect contacts which are arranged to be opened after the arcing contacts open during a circuit opening operation of the circuit interrupter, and closed after the arcing contacts have closed during a closing operation of the circuit interrupter. The disconnect

contacts comprise a stationary disconnect contact member 33 mounted in a terminal cap 35 on the upper end of a hollow insulator 37, and a cooperating movable disconnect contact member 39 in the form of a hollow tubular rod which is mounted in bearing means on the casing 19 for straight line movement in the direction of its longitudinal axis, the axis of movement of the contact member 39 being at an angle to the axis of movement of the arcing contact member 31.

The movable arcing contact member 31 and the movable disconnect contact member 39 are electrically connected in series by means of a resilient connector contact means 53 (Fig. 2) slidably engageable by contact member 31, and by connector strips 55 and 57 (Fig. 2). The latter conductor strip 57 is electrically connected to a similar connector contact means 59 (Fig. 2) that is slidably engageable by the movable disconnect contact member 39.

The hollow insulator 37 may be supported from the right-hand end of the framework 11, and this insulator serves as a housing for transformers and other suitable instruments necessary for the control of the circuit interrupter. External circuit connections to the interrupter are made to a terminal 61 carried by the terminal cap 27 and to a terminal 63 on the terminal cap 35. Thus from the foregoing description, it is apparent that when the circuit interrupter is in closed position, current flows through the interrupter from the terminal 61, through the terminal cap 27, stationary arcing contact 29, movable arcing contact 31, connector contact means 53, conducting strips 55 and 57, connector contact means 59, movable disconnect contact member 39, stationary disconnect contact member 33 and through a flexible shunt conductor (not shown) to the terminal cap 35 and terminal 63. If the movable arcing contact 31 is operated to open circuit position while the interrupter is carrying a load, an arc will be drawn by the movable arcing contact member 31. Extinction of arcs drawn by the movable arcing contact member 31 may be accomplished by any suitable arc extinguishing means but preferably by an arc extinguisher of the fluid blast type which, for example, may be of the form fully disclosed in the copending application of L. R. Ludwig and B. P. Baker, Serial No. 373,856, filed January 9, 1941, and assigned to the assignee of this application. Since the present application is not concerned with the arc extinguishing structure, it is believed that the general designation of the arc extinguishing unit 65 will be sufficient for the purpose at hand.

Fluid under pressure, in this instance compressed air, for extinguishing the arc and also for the operating means of the interrupter may be stored in a tank 67 mounted within the framework 11. Extending from the left-hand end of the tank 67 is a pipe 69 which has mounted thereon and in communication therewith a blast valve mechanism indicated generally at 71. The blast valve mechanism has a housing 73 (Fig. 5) which communicates through a short section of pipe 75 with the passage through the interior of the insulator 13. The passage through the insulator 13 communicates through a pipe 77 and through the hollow insulator 21 with the chamber of the circuit interrupting element 23. Thus a blast of air under pressure from the tank 67 is conducted to the arc extinguisher 65 by way of the pipe 69, blast valve 71, hollow insulator

13, pipe 77 and tubular insulator 21. The blast valve mechanism 71 is of the same construction as that disclosed in the aforementioned copending application of L. R. Ludwig et al., Serial No. 431,394, and consequently only a very brief description thereof will be given since reference to the aforementioned application may be had for details of construction. Briefly, the blast valve mechanism includes a valve 79 in the housing 73 which is biased to closed position by a spring and which is caused to be opened upon energization of a solenoid 83.

The contact members 31 and 39 are operated to open position in a predetermined sequence and also to closed position in a predetermined sequence by a compressed air operating means comprising an operating cylinder 89 having a double acting piston 101 therein (Fig. 4) connected to the lower end of the arcing contact member 31, and an operating cylinder 103 having a double acting piston 105 therein (Fig. 2) connected to the lower end of the movable disconnect contact member 39. The operating cylinder 89 is mounted within the casing 19 and has a lower cylinder head 109 secured thereto by bolts 107, the cylinder head being in turn secured to the bottom plate 111 of the casing 19 by a plurality of bolts (not shown). The lower portion of the arcing contact rod member 31 slidably extends through the offset portion of the pipe 77 and through an opening provided therefor in the upper head of the cylinder 89, the lower end of the contact member being connected to the piston 101. Referring to Fig. 4, the cylinder 89 has a projection 113 formed integral therewith adjacent the upper end, and this projection has a passage 115 leading to the upper end of the interior of the cylinder and a port (not shown) in communication with the passage which is connected by a pipe 117 (Fig. 2) to the passage of the hollow insulator 17. This passage of the hollow insulator 17 is, in turn, connected by a pipe 119 (Fig. 6) to an opening valve mechanism 163 for controlling the flow of compressed air to effect an opening operation of the circuit interrupter. The lower end of the operating cylinder 89 is also provided with an integral projection 121 (Fig. 4) having a passage 123 therein communicating with the lower end of the cylinder, and also has a port (not shown) in communication with the passage which is connected by a pipe 125 (Fig. 2) to the passage through the hollow insulator 15 which conducts air for closing the circuit interrupter. The passage of the hollow insulator 15 is, in turn, connected by a pipe 127 (Fig. 6) to a closing valve mechanism 165 which will be hereinafter described.

The operating cylinder 103 is mounted in the casing 19 and the upper portion thereof projects outside of the casing 19, through an opening provided in an annular casting or supporting member 129 which is secured to the wall of the casing 19 by a plurality of bolts 131. The member 129 serves to support the cylinder 103. The lower end of the operating cylinder 103 fits into a cylinder head 133 which is secured on this end of the cylinder by a plurality of elongated bolts 135, only one being shown. The bolts 135 pass through a flange of the cylinder head 133 and thread into the annular support member 129. The upper end of the operating cylinder 103 fits into a cylinder head 137 which is secured thereon by a plurality of bolts 139, only one being shown. The bolts 139 extend through openings

provided in a flange of the cylinder head 137 and the lower ends of the bolts thread into the angular support member 129, thus securely clamping the cylinder head on the end of the cylinder. A metallic cover 141 is mounted at the upper end of the cylinder head and is secured thereto by a plurality of bolts 143, only one being shown. The bolts 143 pass through a flange of the cover 141 and through the flange of the cylinder head 137. A metallic closure cap 145 is securely clamped over the upper end of the cylinder head 137 by the cover 141, suitable packing gaskets or other packing material being disposed between the cap 145 and the upper end of the cylinder head 137.

The tubular disconnect contact member 39 extends through bearing openings in the cover 141 and end cap 145 into the interior of the cylinder 103, and the lower end of this contact member is connected to the operating piston 105.

The lower cylinder head 133 of the operating cylinder 103 is provided with passages 149 and 151 which communicate with the lower end of the interior of the cylinder 103. The compressed air for closing the disconnect contact member is adapted to flow through these passages to the underside of the piston 105. The upper cylinder head 137 is also provided with passages 153 and 155 which communicate with the interior of the cylinder head at the upper end of the cylinder 103 for conducting the flow of compressed air to the upper side of the piston 105 to effect opening operation of the disconnect contact member 39. A sleet hood 157 is provided for protecting the exposed portion of the cylinder assembly 103.

Compressed air for operating the pistons 101 and 105 to effect opening and closing of the circuit interrupter is derived from the air storage tank 67. For this purpose, the pipe 69 is provided with two branch pipes 159 and 161 (Fig. 6). The pipe 159 leads to the opening valve mechanism generally indicated at 163, whereas the branch pipe 161 leads to the closing valve mechanism indicated generally at 165. Compressed air from the opening valve mechanism 163 is conducted through the pipe 119 and passage of the hollow insulator 17 and pipe 117 to the upper end of the operating cylinder 99 above the uppermost position of the operating piston 101. The closing valve mechanism 165 controls the flow of compressed air from the pipe 161, through the pipe 127, passage of the hollow insulator 15 and pipe 125 to the lower end of the operating cylinder 99 below the lowermost position of the operating piston 101 to effect closing operation of the circuit interrupter.

It is important that the disconnect contact member 39 should be opened only after the arcing contact member 31 has been moved to full open position during a circuit opening operation, and it is also desirable that the disconnect contact member 39 should close after the arcing contact member 31 has reached closed position during a closing operation, in order to eliminate the necessity of providing a blast of arc extinguishing fluid for the arcing contact during the closing operation. In order to accomplish this sequence of operation of the contact members 31 and 39, the operating pistons 101 and 105 are pneumatically interlocked to insure the desired sequence of operation. For this purpose the operating cylinder 99 is provided with a projection 169 (Fig. 4) integral therewith adjacent the upper end, and this projection has an air passage 171 formed therein which communicates at one

end with the interior of the cylinder at a predetermined point below the upper end of the cylinder. The other end of the passage 171 communicates with a port (not shown) in the projection 169 which is connected by a pipe 173 (Fig. 2), passage 177 in support member 129, and a pipe 175 to the passages 153 and 155 leading to the upper end of the operating cylinder 103. The point of entry of the passage 171 into the cylinder 99 is so located that it is uncovered by the piston 101 after the piston has moved downwardly a predetermined distance in an opening direction, so that the operating piston 101 will have overcome static friction and come up to nearly full speed before compressed air is admitted through the pipes 173 and 175 to the upper end of the operating cylinder 103. The construction is such that movable arcing contact member 31 will have reached full open position before the compressed air applied to the upper side of the operating piston 105 starts to move the disconnect contact member 39 to the open position.

A similar projection 179 (Fig. 4) is formed integral with the cylinder 99 adjacent the lower end thereof, and this projection has a passage 181 which communicates at one end with the interior of the cylinder 99 at a point a predetermined distance above the lower end of the cylinder. The other end of the passage 181 communicates with a port (not shown) in the projection 179 which is connected by a pipe 183 (Fig. 2) to the passages 149 and 151 of the cylinder head 133, leading to the lower end of the operating cylinder 103. The point of entry of the passage 181 into the cylinder 99 is disposed to be uncovered by the operating piston 101 after the piston has moved upwardly a predetermined distance in the closing direction, to admit air to the lower end of the operating cylinder 103 beneath the piston 105. The location of the passage 181 is such that the arcing contact member will have been moved to the completely closed position before the compressed air acting on the underside of the operating piston 105 moves the movable disconnect contact member 39 to closed position.

In order to obtain high speed opening and high speed reclosing of the operation of the circuit interrupter, it is necessary to dump the air in the cylinders ahead of the direction of movement of the operating pistons to atmosphere so as to prevent air ahead of the pistons from unduly retarding the movement thereof. Two dump valves 187 and 197 (Fig. 4) are provided for this purpose. The dump valve 187 is mounted in the projection 179 at the passage 181 thereof, and this valve has a rod 189 connected thereto, the upper end of which is connected to a piston 191 movable in a cylinder 193 of the projection 113. The dump valve 187 is biased to closed position by a spring 207, and it is adapted to be operated to open position by the piston 191 immediately upon the flow of compressed air to the upper side of the arcing contact operating piston 101. Opening of the valve 187 opens the lower end of both cylinders 99 and 103 to atmosphere through an atmosphere exhaust port 195, so that the air below the two operating pistons will be at low pressure and will not unduly retard the opening movement of the two pistons. The other dump valve 197 is mounted in the projection 169 of the cylinder 99 and has a rod 199 connected thereto, the lower end of which is connected to a piston 201 mounted in a cylinder 203 of the projection

121. The dump valve 187 is biased to closed position by a spring 207 and is adapted to be opened by the piston 201 immediately upon the flow of compressed air to the lower end of the operating cylinder 88 through the passage 123. Opening of the dump valve 187 connects the upper ends of both cylinders 88 and 103 to atmosphere through an exhaust port 205, thereby causing the air above the operating pistons to be at a low pressure, so that it will not retard the closing movement of the operating pistons.

The opening valve mechanism 163 and the closing valve mechanism 165 are of the same construction as disclosed in the aforementioned copending application of L. R. Ludwig et al., Serial No. 431,394, and only a brief description thereof will be given in this application, as the details of construction of the valve mechanisms are not necessary to a complete understanding of the present invention. Referring to Fig. 6, the opening valve mechanism 163 has a valve 209 which is biased closed and which is caused to be opened by air pressure from the pipe 159 upon energization of a solenoid 211. Similarly, the closing valve mechanism 165 has a valve 213 which is biased closed and which is caused to be opened by compressed air from the pipe 161 upon energization of a solenoid 215. The valve mechanisms 163 and 165 are pneumatically interlocked by means of a piston (not shown) in the valve mechanism 165 and by a pipe 218 connecting the housings of the valve mechanisms 163 and 165 as disclosed in the aforementioned copending application of L. R. Ludwig et al., Serial No. 431,394, so that an opening impulse will always take precedence over a closing impulse.

The control circuits for controlling the solenoid 93 of the blast valve mechanism 71 and the solenoids 211 and 215 of the opening and closing valve mechanisms are the same as disclosed in the aforementioned copending application of L. R. Ludwig et al., Serial No. 431,394, and are not shown in this application as the details thereof are not necessary to a complete understanding of the present invention. It is sufficient to state that the solenoid 93 of the blast valve mechanism and the solenoid 211 of the opening valve mechanism are adapted to be simultaneously energized to effect opening of their respective valves in response to the operation of an opening relay. The opening relay is caused to be energized in response to the operation of an overload current responsive protective relay or by the closing of a manual opening control switch. The solenoid 93 of the blast valve 71 is caused to be deenergized by auxiliary contacts of an auxiliary switch means 221 (Fig. 1) as soon as the disconnect contact member 38 starts its opening movement; consequently, the blast valve 71 is returned to its closed position. As soon as the opening operation of the circuit interrupter is completed and the disconnect contact member 38 reaches full open position, the opening relay is deenergized by the opening of another pair of auxiliary contacts of the auxiliary switch means 221, so that the opening valve returns to closed position. The solenoid 215 of the closing valve means is caused to be energized by the operation of a closing relay. The closing relay is, in turn, caused to be operated by either a reclosing relay or by a manual closing control switch. As soon as the closing operation of the circuit interrupter has been completed and the disconnect contact member 38 has reached the fully closed position, the closing relay is deenergized by the opening of a pair

of auxiliary contacts of the auxiliary switch means 221.

The auxiliary switch 221 (Fig. 1) may be of any conventional multipole construction and is adapted to be operated in accordance with the position of the movable disconnect member 38, by means of a rotatable twisted square rod 222 rotatably mounted in the lower head 133 and extending into the cylinder 103 for substantially the entire length of the cylinder. The contact member 38 is of tubular construction, and the operating piston 105 has a square opening (not shown) in alignment with the tubular contact member for slidably engaging the twisted square rod 222. The operating piston 105 and tubular contact member 38 slide telescopically on the twisted square rod 222 and rotate the rod in one direction or the other depending upon the direction of movement of the operating piston. A crank 223 (Fig. 2) secured to the lower end of the twisted square rod is connected by a linkage 225, 227, 229, 231 (Fig. 1) to the operating lever of the auxiliary switch 221.

The construction of the circuit breaker as thus far described in detail above is substantially identical to the circuit breaker disclosed in the copending application of L. R. Ludwig et al. Serial No. 431,394.

The piston 101 which drives the arcing contact member 31 has a relatively short stroke and as a result can be safely decelerated by a mechanical bumper means. The contact member 38, however, is driven by the operating piston 105 which has a long stroke, and because of this and the high speeds attained during its travel, it must be decelerated considerably before the end of its stroke in order to prevent damage to the apparatus from shock and impact at the end of the stroke. In accordance with the present invention, the operating means for the movable contact member 38 is provided with an improved air shock-absorbing means for decelerating the contact member 38 and its operating piston 105 as these elements approach the end of the operating stroke, and to bring these moving elements to rest at the extreme end of the stroke without shock, stalling or rebound. The shock-absorbing means comprises an automatic throttle valve associated with each end of the contact operating cylinder 103. Each valve permits free flow of compressed operating air in a forward direction into the corresponding end of the cylinder and is operative to partially throttle the reversely flowing air being exhausted from the corresponding end of the cylinder to thereby decelerate the moving piston by the dashpot action of the air being compressed by the moving piston. Each automatic valve is also operative to remain in open position after it is opened by forwardly flowing air for a predetermined short time interval after the forwardly flowing operating air is shut off so that the valve element will thereby exert either no throttling effect or a lesser throttling effect if a reverse switching operation occurs within a predetermined time interval after the initiation of the preceding switching operation.

Referring to Figs. 2 and 3, each of the automatic valve devices comprises a piston-type cup-shaped valve element 235 associated with the air passage leading to the corresponding end of the contact operating cylinder 103. The valve element 235 is slidably mounted in a valve cylinder 237 which is threaded into an opening provided therefor in the corresponding head of the

contact operating cylinder 103 adjacent the air passage leading to the end of the cylinder. The valve element 235 is biased to closed position against its valve seat in the air passage by means of a helical compression spring 239 which is disposed between the automatic valve element 235 and the closed end of the valve cylinder 237. A small bleeder passage 240 is provided in the valve cylinder 237 adjacent the closed end thereof for a purpose which will be hereinafter described.

One of the automatic valve devices is mounted in the cylinder head 137 for the upper end of the contact operating cylinder 103 and the piston type valve element 235 of this valve device is associated with the air passage 153 which communicates with the upper end of the operating cylinder 103. The valve element 235 is biased to closed position against a valve seat 241 provided in the passage 153, and the valve seat is provided with one or more leak holes 243 connecting the passages 153 and 155 for the purpose of providing a predetermined degree of throttling of the air being exhausted through the passage 153 and the previously described dump valve to atmosphere. With the proper degree of throttling determined by the size of the leak hole 243, the operating piston 105 can be made to come to rest at the extreme end of its stroke without stalling or rebound and without developing high impact forces.

The other automatic valve device is of the same construction and is mounted in the lower cylinder head 133 of the contact operating piston. The automatic valve element 235 for this end of the contact operating cylinder is associated with the passage 149 leading to the lower end of the contact operating cylinder 103, and the valve spring 239 biases this valve element to closed position against a seat 241 provided in the passage 149. The valve seat 241 is provided with one or more leak holes 243, the same as described in connection with the valve device for the upper end of the contact operating cylinder.

When compressed air is caused to flow through the pipe 175 to effect movement of the disconnecting contact member 39 to open position, the air impinges against the automatic valve piston 235, causing it to recede into the valve cylinder 237 against the restraining force of the spring 239, expelling air from the valve cylinder 237 through the bleeder passage 240. Thus, the valve operates to let driving air flow freely through the passages 153 and 155 into the upper end of the contact operating cylinder 103 to move the operating piston 105 and disconnect contact member 39 downwardly to open position. If no further operation takes place within a predetermined short time interval, the piston valve 235 is returned to closed position by the biasing spring 239 after the opening air is shut off by the closing of the opening valve mechanism 163. This opening valve mechanism 163 has a leak hole (not shown) which allows the air in the pipes 175 and 117 to leak out to atmosphere after closing of the opening valve mechanism. The short predetermined time interval required for the valve element 235 to return to closed position is determined, however, by the size of bleeder passage 240. This time delay is very important if the switch is to be closed immediately after the opening operation. In this case, there will still be high pressure air in the portion of the operating cylinder 103 above the operating piston 105 and the degree of shock absorption or

deceleration would be many times higher than on a normal closing operation, if the valve element 235 returned immediately to closed position. Since the valve element 235 requires a predetermined time interval to return to closed position, it will exert a lesser degree of throttling effect on the air being exhausted through the passage 153 if a reclosing operation occurs within the predetermined time interval after an opening operation. Thus, the degree of shock absorption may be substantially the same on quick reclosing operations as in the case of normal closing operations.

During the movement of the contact operating piston 105 to open position, the throttle valve 235 associated with the lower end of the contact operating cylinder 103 serves to partially throttle the air being exhausted from the lower end of the contact operating cylinder below the operating piston 105. The opening movement of the contact operating piston is thus decelerated as the piston approaches open position, that is to say, its lower end position.

When compressed air is caused to flow through the pipe 183 to operate the contact member 39 to closed position, the operating air impinges against the piston valve 235 associated with the lower end of the operating cylinder causing the valve element to recede into the valve cylinder against the force of the spring 239. Thus, this valve element is moved to open position and lets the driving air flow freely through the passages 149 and 151 into the lower end of the contact operating cylinder to move the operating piston 105 to the upper end of the operating cylinder and close the switch. The upper valve 235 for the upper end of the cylinder throttles the air exhausted from the upper end of the cylinder to decelerate the movement of the piston as it approaches its upper end position. If no further operation takes place within a predetermined short time interval, the valve element 235 is returned to closed position after the flow of operating air is shut off by the closing valve mechanism 165. However, if a switch opening operation occurs immediately after, or within a short predetermined time interval after, the switch closing operation, the piston valve 235 is still in open position and, consequently, exerts a lesser degree of throttling on the air being exhausted from below the contact operating piston 105 than in the case of a normal opening operation, when the valve is in its closed position.

It is believed that the details of operation of the circuit interrupter will be clearly understood from the foregoing description. Briefly the operation of the circuit interrupter is as follows: Assuming the circuit breaker to be in open position as shown, a closing operation of the circuit breaker is caused to take place upon energization of the solenoid 215 of the closing valve mechanism 165. Opening of the valve 165 causes compressed air to flow from the tank into the lower end of the arcing contact operating cylinder 99 to move the arcing contact member upwardly to closed position. The flow of compressed air to the lower end of the arcing contact operating cylinder 99 immediately causes opening of the dump valve 187, thereby establishing an exhaust connection to atmosphere for the upper ends of each of the cylinders 99 and 103. After the arcing contact operating piston 101 is moved upwardly a predetermined distance, it uncovers the passage 181 so that compressed air then flows through the pipe 183 to the lower end of the

disconnecting contact operating cylinder 103. By the time the arcing contact member 31 reaches closed position, the compressed air acting on the underside of the operating piston 105 starts to move the disconnect contact member 38 to closed position, and finally completes operation of the contact member 31 to closed position. The automatic valve element 235 associated with the upper end of the operating cylinder 103 is in closed position, and in this position acts to partially throttle the air being exhausted from the upper end of the cylinder 103 through the passage 153 and out through the dump valve 197 thereby decelerating the movement of the piston 105 as it approaches closed position.

An opening operation of the circuit interrupter is produced upon energization of the solenoid 211 of the opening valve mechanism 163. Opening of the valve 163 causes compressed air to flow from the tank 87 into the upper end of the arcing contact operating cylinder 99 to move the arcing contact member 31 to open position. The flow of compressed air to the upper end of the operating cylinder 99 immediately causes opening of the dump valve 197, thereby opening the lower ends of both cylinders 99 and 103 to atmosphere through the exhaust port 195. After the operating piston 101 is moved downwardly a predetermined distance, it uncovers the passage 171 so that compressed air then flows through the pipe 175 to the upper end of the disconnect contact operating cylinder 103. This flow of compressed air effects opening operation of the disconnect contact member 38, driving the piston 105 downwardly to the lower end of the cylinder. The automatic throttle valve 235 for the lower end of the operating cylinder 103 is in closed position, and in this position acts to partially throttle the air being exhausted from the lower end of the disconnect contact operating cylinder 103, thereby decelerating the movement of the piston 105 as it approaches its lower end position.

As previously pointed out, each of the automatic valves 235 is opened by the forwardly flowing operating air and remains open for a predetermined short interval of time after the forwardly flowing operating air is shut off. By reason of this time delay action in the return of the valve members 235 to closed position, these valves will exert a lesser amount of throttling effect whenever a reverse switching operation occurs immediately, that is within a predetermined short time interval after the preceding operation. Thus, the degree of shock absorption will be substantially the same for quick reverse switching operations as for normal operations.

While the invention has been disclosed in accordance with the provisions of the patent statutes, it is to be understood that various changes in the structural details thereof may be made without departing from some of the essential features thereof. It is desired, therefore, that the language of the appended claims be given the broadest reasonable interpretation permissible in the light of the prior art.

We claim as our invention:

1. A circuit interrupter having a movable contact member, operating means comprising an operating cylinder and a piston in said cylinder for actuating said contact member, means forming a fluid passage communicating with one end of said cylinder for the flow of fluid into and out of said cylinder, means for supplying fluid under pressure to said cylinder through said passage,

a throttle valve associated with said passage having a closed position in which it partially throttles the flow of fluid out of said cylinder through said passage, said valve being biased to closed position and operated to open position by the forward flow of fluid into said cylinder through said passage to permit free forward flow of fluid, and means for delaying the return of said throttle valve to closed position for a predetermined time interval after each opening thereof.

2. A circuit interrupter having a movable contact member, operating means for actuating said contact member comprising an operating cylinder, a fluid pressure operated piston in said cylinder connected to said contact member, means for supplying fluid under pressure to said cylinder to actuate said contact member, means for automatically exhausting fluid ahead of the moving piston and a valve device for normally throttling the exhaust of fluid from said cylinder a predetermined amount and for throttling the exhaust of fluid a lesser amount when a reverse operation of the contact member occurs within a predetermined time interval after initiation of the preceding operation of the contact member.

3. A circuit interrupter having a movable contact member, operating means for moving said contact member to open and to closed position comprising an operating cylinder, a piston in said cylinder connected to said contact member, means for supplying fluid under pressure to one end of said cylinder to effect closing operation of the contact member, said operating means including means for automatically exhausting fluid from said one end of the cylinder during opening operation of the contact member, and a valve device normally operative to throttle the exhaust of fluid from said one end of the cylinder a predetermined amount and operative to throttle the exhaust of fluid from said one end of the cylinder a lesser amount when an opening operation occurs within a predetermined time interval after the initiation of a closing operation.

4. A circuit interrupter having a movable contact member, operating means for moving said contact member to open and to closed position comprising an operating cylinder, a piston in said cylinder connected to said contact member, means for supplying fluid under pressure to said cylinder to effect opening operation of said contact member, means for automatically exhausting fluid from said cylinder ahead of the moving piston, and a valve device normally operative to throttle the exhaust of fluid from said cylinder a predetermined amount and operative to throttle the exhaust of fluid a lesser amount if a closing operation is initiated within a predetermined time interval after the initiation of an opening operation.

5. A circuit interrupter having a movable contact member, operating means comprising an operating cylinder, a piston in said cylinder for actuating said contact member, means for supplying fluid under pressure to one end of said cylinder to operate said piston, means for automatically exhausting fluid from said end of the cylinder upon reverse movement of said piston, said last mentioned means including an automatic throttle valve biased to a closed position in which it throttles the exhaust of fluid from said cylinder a predetermined amount, said valve being moved to an open position when fluid under pressure is supplied to said one end of the

cylinder and maintained in open position for a predetermined interval of time after the supply of fluid under pressure to said cylinder is shut off.

6. A circuit interrupter having a movable contact member, compressed gas operating means therefor comprising an operating cylinder, a reciprocally movable piston in said cylinder for actuating said contact member, means for supplying compressed gas to one end of said cylinder to operate said piston in one direction, means for automatically exhausting gas from said one end of the cylinder to atmosphere upon reverse movement of said piston, said last mentioned means including an automatic throttle valve biased to a closed position in which it throttles the flow of exhaust gas a predetermined amount, said valve being operated to an open position when compressed gas is supplied to said one end of the cylinder, and means for delaying the return of said valve to closed position for a predetermined time interval after the supply of compressed gas to said end of the cylinder is shut off.

7. In a circuit interrupter having a movable contact member, compressed air operating means therefor comprising an operating cylinder and a piston in said cylinder for actuating said contact member, means forming an air passage communicating with one end of said cylinder for the flow of air into and out of said end of the cylinder, means for supplying compressed air to said end of the cylinder through said passage, and an automatic valve device comprising a piston type throttle valve element associated with said passage having a closed position in which it throttles the flow of exhaust air from said cylinder out through said passage a predetermined amount, a valve cylinder in which said valve element is movable, a spring in said valve cylinder biasing said valve element to closed position, said valve element being operated to an open position in said valve cylinder by the forward flow of compressed air to said operating cylinder, said valve cylinder having a closed end provided with a leak hole to atmosphere for delaying the return of said valve element to closed position for a predetermined time interval after the supply of compressed air to said cylinder is shut off.

8. A circuit interrupter having a movable contact member, compressed air operating means therefor comprising an operating cylinder, a double acting piston in said cylinder for moving said contact member to open and to closed circuit position, means for supplying compressed air to the opposite ends of said cylinder to effect opening or closing operation of the contact member, means operated pneumatically by the flow of operating compressed air to either end of said cylinder for automatically exhausting air from the other end of said cylinder to atmosphere, and throttle valve means normally operative to throttle the flow of exhaust air out of said cylinder a predetermined amount, said throttle valve means being automatically operable to throttle the exhaust air a lesser amount when a reverse switching operation occurs within a predetermined time interval after the initiation of the preceding operation.

9. In a circuit interrupter having a movable contact member, compressed air operating means

comprising an operating cylinder, a double acting piston in said cylinder for moving said contact member to open and to closed circuit position, means for supplying compressed air to one end of said cylinder to effect operation of said contact member to one of said positions and for supplying compressed air to the opposite end of said cylinder to effect operation of said contact member to the other of said positions, a dump valve pneumatically operated by the flow of compressed air to said one end of the cylinder to automatically cause air to be exhausted from the other end of said cylinder, and a throttle valve biased to a closed position in which it throttles the flow of exhaust air from said other end of the cylinder a predetermined amount, said throttle valve being operated to an open position by the forward flow of operating compressed air to said other end of the cylinder, and means for delaying return of said throttle valve to closed position for a predetermined time interval after the forward flow of air to said other end of the cylinder is shut off.

10. In a circuit interrupter having a movable contact member, compressed air operating means comprising an operating cylinder, a double acting piston in said cylinder for moving said contact member to open and to closed circuit position, each end of said cylinder having an air passage communicating therewith for the flow of air into and out of said cylinder, means for supplying compressed air to said cylinder through either of said passages to operate the piston, means for simultaneously exhausting air from the opposite end of said cylinder to atmosphere through the air passage of said opposite end of the cylinder, an automatic throttle valve associated with each of said air passages, each of said throttle valves being biased to a closed position in which it throttles the flow of exhaust air a predetermined amount and operated to open position by the forward flow of compressed air to said cylinder and remaining open for a predetermined time interval after the forward flow of compressed air is shut off.

11. In a circuit interrupter having a movable contact member, compressed gas operating means comprising an operating cylinder, a double acting piston in said cylinder for moving said contact member to open and to closed circuit position, each end of said cylinder having a passage communicating therewith for the flow of gas into and out of said cylinder, means for supplying compressed gas to either end of said cylinder through said passages, means operated upon the flow of compressed gas to either end of said cylinder for automatically dumping exhaust gas from the opposite end of said cylinder through the passage of said opposite end of the cylinder, an automatic throttle valve associated with at least one of said passages, said valve being biased to a closed position in which it throttles the flow of exhaust gas through said passage a predetermined amount and operated to open position by the forward flow of compressed gas through said passage to said cylinder, and remaining open as long as the pressure of the gas in the portion of the cylinder communicating with said passage exceeds a predetermined value.
